POURING SPOUT

Raymond W. Emery and Vernon L. Sprague,
Warren, Ohio, assignors to The Niles Steel
Products Company, Niles, Ohio, a corporation
of Ohio

Application March 12, 1936, Serial No. 68,371

4 Claims. (Cl. 221—27)

This invention relates to improvements in pouring spouts, particularly spouts that are adapted to be retracted into the container for protection during shipment and handling.

5 One of the objects of the invention is the provision of a spout construction of this character which shall have a rigid mounting in the container when it is in extended or operative position.

10 Another object of the invention is the provision of a mounting for the spout such that the joint between the container and the spout in the operative position of the latter shall be a metal to metal one of a nature such that a good sealing of 15 the joint is effected.

15 Other objects and features of novelty will appear as we proceed with the description of that embodiment of the invention which, for the purposes of the present application, we have illustrated in the accompanying drawing, in which

Fig. 1 is an elevational view of a metal pail in which the invention is incorporated, the pail being shown resting upon its side, parts of the pail being broken away and other parts shown 25 in section in order to more fully illustrate the invention.

Fig. 2 is a fragmental cross sectional view on a larger scale, showing the spout in retracted or inoperative position.

30 Fig. 3 is a view similar to Fig. 2, but with the spout in extended or operative position.

Fig. 4 is a fragmental plan view looking down upon the head of the pail, the spout being shown in extended position, and

35 Fig. 5 is a perspective view of a modified form of the spout.

In the drawing we have shown at 10 a metal pail of more or less conventional form intended for the packaging of oil, alcohol and various other liquid materials. This pail is illustrated in the drawing in pouring position, its normal position being upright. At one end the pail proper is open, its edge being finished with a bead 11. When the pail is filled with liquid this open end is closed by 40 a cover or head 12, also of sheet metal, which is removably secured to the barrel in any approved fashion, as for instance by means of tabs or lugs 13 which may be bent inwardly beneath the bead, a ring gasket 14 being thereby compressed between the bead and the outturned flange 15 of the head, sealing the container.

In the head 12, preferably near the rim thereof, we form a circular opening in which is mounted a collar 16, preferably by means of a lock joint 17. This collar is so formed as to take a closing cap,

for example the collar may be provided with an encircling groove 18 adapted to receive the flexible inwardly bent edge of a resilient metal cap 19 provided with a gasket 20 for engagement with a circular seat 21 on the collar.

5 The collar structure comprises an inner sleeve 22 which is separated somewhat from the outer wall of the collar. This sleeve is circular in cross section about an axis which extends at an angle to the main axis of the collar and the axis of the 10 pail likewise. At the inner end of the sleeve there is a band, indicated at 23, which is flared, that is to say it is tapered away from the inner end. This flare or taper is relatively small, for example twenty thousandths to the inch. The band 23 15 however may be considerably less than an inch in width. The sleeve 22 is preferably formed of metal tubing flanged at its outer end and soldered, welded or otherwise permanently and rigidly joined to an inwardly extending flange 26 on the 20 remaining portion of the collar 16.

In the flange 26 of the collar between the sleeve 22 and the seat 21 we form an opening 24 which serves as a vent opening. A vent tube 25 is soldered or welded to the collar within this opening, and extends for a short distance inwardly in a curve alongside the sleeve 22 and thence in a straight line beneath the head 12 of the pail to a position near the rim upon the opposite side of the center of the head. The vent opening is of 30 course closed when the spout is retracted and the closing cap 19 is in place, as illustrated in Fig. 2.

The pouring spout 27 is generally cylindrical in form. Its outer end is preferably cut at an angle so as to be parallel with the pail head, and it may 35 be reenforced by a rebent edge 28 if desired. The lower part of the forward end of the spout has a lip 29, the purpose of which is to prevent liquids, particularly liquids that are highly fluid, from backing up onto the exterior surface of the spout. 40 This lip 29 also serves as a stop when the spout is pushed into the sleeve 22, as indicated in Fig. 2.

The spout 27 is formed from a sheet of thin gauge metal which is flanged along its longitudinal edges and rolled up to bring the flanges together, after which the flanges are joined by solder, forming a longitudinal internal rib 30 along the top surface of the spout. This rib at the forward end is enlarged and perforated transversely. The ends of the wire bail 31 are mounted in this perforation. Bail 31 is formed of 45 somewhat resilient material which is so shaped that in its natural condition the ends are crossed. Near the ends also there are formed small reverse bends 32 which bear against the sides of 50

rib 30. Because of the resilience of the ball these reverse bends 32 provide friction surfaces that by engagement with the rib 30 tend to hold the bail 31 in any adjusted position. Hence when the bail is swung out and used as a finger hold for pulling the spout out to operative position, the bail remains in its outwardly extended position, indicated in Fig. 3, where it is out of the way of the liquid when the latter is poured from

10. the container.

The metal of the spout is preferably of some-
what lighter gauge than that of the sleeve 22,
and at its inner end it is flared or reversely ta-
pered with the same degree of taper as the band
15 23, and this flared portion of the spout is marked
33 on the drawing. The flared portion 33 may
be a trifle wider than the flared band 23. The
inner extremity of spout 27 is not reenforced in
any manner, and accordingly its natural resili-
20 ence is not interfered with. It may therefore
conform very readily and effectively with the
flared band 23 when the spout is pulled out to
operative position.

In Fig. 5 we have illustrated a spout of slightly
25 modified form, having a cylindrical body 27 and
an inner flared band 33. In this form the metal
of the spout at the pouring end is pinched in-
wardly to some extent, as indicated at 34 and
30 35, leaving a narrow pouring groove 36, which is
useful when the liquid in the pail must be trans-
ferred to small mouthed bottles or other con-
tainers. In thus forming the groove 36 we take
35 precautions to prevent the inward bending at
the points 34 and 35 from forcing the metal of
the groove outwardly, as the spout must be ca-
pable of being fully retracted to the position
shown in Fig. 2.

In order to take liquid from a pail or drum
40 equipped with the spout of this invention, the
operator first removes the cap 19 from the pail
while the latter is sitting on its bottom end. He
then grasps the bail 31 and pulls the spout 27
45 outwardly to the position of Fig. 3. As soon as
the flared or tapered portions 33 and 23 of the
spout and sleeve come into tight engagement, fur-
ther movement is of course stopped and the joint
50 between the spout and the sleeve is then liquid-
tight. It is also rigid and secure. Rigidity is
effected not only by the engagement of the flared
55 portions, but also by the engagement of the
cylindrical portion of the spout with the cylin-
drical portion of the sleeve. This latter engage-
ment, while not liquid-tight, is close enough to
provide an excellent mechanical connection.
There results a spout mounting which is firm
and secure and capable of resisting all forces nat-
urally to be encountered except force applied

inwardly along the axis of the spout. The rigid-
ity of the spout mounting is sufficiently good to
permit supporting the filled container upon its
spout during the pouring operation. In so far as
the sealing effect is concerned, there is no de-
pendence upon gaskets, which sooner or later
5 become leaky, and the metal to metal flared bands,
if carefully formed, produce an entirely liquid-
tight connection.

Variations from the described structure may
10 be employed. Accordingly we desire it to be un-
derstood that the scope of the invention is to
be regarded as defined exclusively by the appended
claims rather than by the foregoing description
or the accompanying illustration.

Having thus described our invention, we claim:

1. In a container, a sleeve mounted in a wall
thereof, said sleeve having a portion of generally
cylindrical contour, a pouring spout of generally
20 cylindrical contour adapted to slide in said sleeve
from inner inoperative position to outer operative
position and vice versa, the outer end of said
spout having portions pinched inwardly to pro-
vide a narrow pouring groove, said outer end of
25 the spout however lying entirely within the cyl-
indrical portion extended, whereby the spout may
be slid into the sleeve to a flush position.

2. In a container of the character described, a
head, a collar mounted in the head and projecting
outwardly therefrom, said collar being substan-
tially circular about an axis perpendicular to the
head, a sleeve carried by the collar and extending
30 inwardly therefrom, said sleeve being circular
about an axis inclined to the first named axis,
and a generally cylindrical spout slidably mount-
ed in said sleeve for movement outwardly to op-
erative position and inwardly to inoperative po-
sition, said sleeve and spout having metal to metal
35 engaging portions at their inner ends adapted to
limit the outward movement of the spout and
40 seal the joint between spout and sleeve.

3. In a container, a collar, a pouring spout slid-
able in said collar either to extended or retracted
position, and a finger hold pivotally mounted in
the forward end of said spout at one edge thereof,
45 said pivotal mounting providing friction sufficient
to maintain the finger hold in a set position
against accidental displacement.

4. In a container, a collar, a pouring spout slid-
able in said collar either to extended or retracted
position, said spout comprising an inwardly di-
rected rib, and a finger hold pivotally mounted
in said rib near the forward end of the spout,
50 said finger hold being adapted to swing into the
spout in its inoperative position.
